UNITED STATES PATENT OFFICE.

EARL J. HORNBERGER, OF CLEVELAND, OHIO, ASSIGNOR TO JOHN G. OLIVER,
DOING BUSINESS AS BARDONS AND OLIVER, OF CLEVELAND, OHIO.

AUTOMATIC CHUCK AND ROLLER FEED.

Application filed December 6, 1926. Serial No. 152,880.

My invention as shown in the drawings and described in this specification consists of an apparatus which can be attached to a standard hollow spindle turret lathe and is 5 adapted to take the place of hand operated stock feeding and chucking mechanism. However, as will be seen by those skilled in the art, my invention is not limited to the exact type of apparatus shown and described 10 but may be built as an integral part of the lathe and may be applied to any type of machine tool for which it is suitable.

Among the objects of my invention are:— the provision of apparatus which can be 15 readily attached to a standard turret machine and which will automatically perform the functions of the hand operated stock chucking and feeding mechanism; the provision of fluid pressure operated stock chucking and feeding means controlled by a single valve; the provision of power operated stock feeding means which will feed any desired length of stock through the hollow spindle of the lathe. The above and other 20 objects of my invention will be evident from the drawings and the following specification.

My invention is shown in the accompanying drawings in which:—

30 Fig. 1 is a vertical longitudinal section showing my invention applied to a hollow spindle lathe;

Fig. 2 is a fragmentary elevation showing a part of the roller feed mechanism;

35 Fig. 3 is a fragmentary plan view showing my invention;

Fig. 4 is a horizontal section on line IV—IV of Fig. 1;

Fig. 5 is a vertical section on line V—V of 40 Fig. 1;

Fig. 6 is a vertical section on line VI—VI of Fig. 1.

Referring to the drawings, the piston 1 is held in place on piston rod 2 by means of the nut 3 and is adapted to reciprocate in the cylinder 4. Cylinder 4 has a downwardly extending flange 5 and an upwardly extending portion 6. The horizontal rod 7 is held at one end in an aperture 8 in the main frame 45 9 of the machine. The upwardly extending portion 6 of the cylinder 4 is drilled to fit the rod 7 which serves as a support for the cylinder and its attached parts, as shown in Fig. 1. A tie rod 11 is secured to the main frame 9 by the nuts 12 and extends out

through a hole in the downwardly extending flange 5 of the cylinder 4. The end of rod 11 which extends through the hole in the flange 5 is threaded and fitted with nuts 13 and 14 which are adapted to be tightened against the sides of the flange 5, thus holding the cylinder 4 from longitudinal movement. If, however, it is desired to move the cylinder 4 longitudinally for adjustment, it can be readily accomplished by turning both the nuts 13 and 14 toward or away from the main frame 9.

The piston 1 is adapted to be moved in the cylinder 4 in either direction by means of fluid under pressure such as compressed air or liquid under pressure. Fig. 1 shows the piston in its position nearest the cylinder head 15. When in this position, piston rod 2 extends out through the stuffing box 16, which is in the cylinder head 17, and has a bearing at the outer end of frame 18 which is an integral part of cylinder head 17. The cross head 19 is adjustably attached to the piston rod 2 by means of the nuts 20 and 21 and extends through slots 22 and 23 in the frame 18. This cross head 19 moves with the piston rod 2 and the slots 22 and 23 serve as guides and bearings for its movement. Pivoted at the ends of cross head 19 are the horizontal links 24 and 25 which extend toward the cylinder 4 and are disposed on either side of it. These links 24 and 25 are pivotally connected by screws 26 to the vertical levers 27 and 28 which are pivotally mounted on the pins 29. The pins 29 are attached to the upwardly extending portion 6 of the cylinder 4. The upper ends of the vertical levers 27 and 28 are pivotally connected to the chuck actuating collar 30 in known manner, as shown in Figs. 1 and 3.

When the piston 1 is in the position shown in Fig. 1 the linkage above described holds the chuck actuating collar 30 and the cone wedge 31 in a position to hold the chuck fingers 32 apart, thus causing the gripping of the work in the chuck jaws. The chuck shown in the drawings is of the push-out type, but it will be evident to one skilled in the art that a pull-back type may be used.

When the control valve of known type (not shown) is turned to allow the fluid under pressure to enter through pipe 33 and to open pipe 34 to the atmosphere or to an exhaust pipe connection, the piston 1 will be forced to the opposite end of the cylinder 4 and

the piston rod 2, the cross head 19, the horizontal links 24 and 25 and the lower ends of the vertical levers 27 and 28 will be moved in the same direction. The vertical levers 27 and 28, however, are pivoted on the fixed pins 29 so that a movement of the lower ends of these levers in one direction causes the upper ends to move in the opposite direction. Thus the chuck actuating collar 30 and the cone wedge 31 will be moved toward the main frame 9 of the machine when the piston 1 moves in the opposite direction and the fingers 32 will be released, releasing the grip of the chuck upon the stock and allowing it to be fed into working position in the machine by the automatic feed mechanism which will be described later.

It is evident that when the fluid control valve is turned to allow the fluid under pressure to enter the cylinder through pipe 34 and opens the pipe 33 to the atmosphere or exhaust pipe connection the piston will move toward the cylinder head 15 and through the movement of the linkage, above described, the cone wedge 31 will be forced between the fingers 32, spreading them and causing the chuck to grip the stock. As long as the fluid control valve is left in one position, the piston will be held in its corresponding position and the stock will either be held tightly by the chuck or be loose for feeding.

The valve which controls the flow of the fluid under pressure may be of any desired type which will shut off the fluid supply, and which will open one end of the cylinder to the atmosphere or exhaust pipe connection when the other end is opened to the fluid under pressure. I prefer that this valve be operated by a single manually operated handle having three positions: (1) off, (2) stock chucked, and (3) stock loose. However, it is evident that any suitable mechanically and automatically operated type of valve may be used.

It will be seen from the drawings and the above description that the stock chucking mechanism used is the same as that used in my application, Serial No. 120,755 filed July 6, 1926.

The mechanism employed for feeding the stock 35 through the hollow rotating spindle 35^a of the machine is operated by the movement of the same piston 1 as operates the stock chucking mechanism. The stock feeding rolls 36, 37 may be continuously driven by suitable gearing to the machine spindle in the following manner:

The gear 38 mounted upon spindle 35^a drives the gear 39 which is mounted on the stud 40 which may be secured to the main frame 9. The gear 39 drives the worm 41 through the flexible shaft 42. The worm 41 in turn drives the worm gear 43 which is keyed to one end of shaft 44 which has bearings in the bracket 45 which is supported

by frame 18. On the other end of shaft 44 is mounted a gear 46 which meshes with another gear 47 directly below it and mounted on a shaft 48 which also has its bearings in bracket 45. As seen in Fig. 2 gear 46 meshes with a gear 49 which is attached to one end of the shaft of the stock feeding roll 36 and gear 47 meshes with a gear 50 which is attached to one end of the shaft of stock feeding roll 37. Thus it will be seen that the rolls 36 and 37 are driven from the gear 38 through the gears and flexible shaft above described. It will be understood that any other suitable means may be employed for driving one or both of the stock feeding rolls.

The shaft of roll 36 is mounted in arms 51 which are pivoted on shaft 44 between the arms 52 of the bracket 45. The shaft of roll 37 is mounted in arms 53 which are pivoted on shaft 48 in like manner. The arms 51 have gear segments formed on them, the common axis of said gear segments being the center about which the arms are pivoted. Also the arms 53 have integral gear segments which mesh with those on arms 51 and have as their common axis the shaft 48. The arms 53 have downwardly extending portions 54 which are connected at their lower ends by the rod 55 which fits in the slot 56 in the sliding sleeve 57. The sleeve 57 is adapted to slide on the piston rod 2, its movement being limited by the adjustable nuts or tappets 58 and 59. A spring 60 and washer 61 are placed between the nut 59 and sleeve 57 for a purpose which will be described.

The operation of the roller feed mechanism is as follows:

When the machine is in operation the rolls 36, 37 are continuously driven in a direction tending to feed the stock 35 through the hollow spindle and into working position. The stock 35 is fed forward only when the rolls 36, 37 are gripping it. To cause the rolls 36, 37 to grip the stock 35 the downwardly extending portions 54 of the arms 53 must be moved away from the cylinder 4. This causes the arms 53 which support the shaft of roll 37 to swing upward forcing the roll 37 against the bottom of the stock 35, and the gear segments on the arms 53 to co-act with those on arms 51 to cause the arms 51 to swing downward and bring the roll 36 into contact with the top of the stock 35.

The opposite action takes place when the downwardly extending portions 54 of arms 53 are moved toward the cylinder 4, the rolls 36, 37 then being swung out of contact with the stock 35. Thus the movement of the piston 1 and piston rod 2 causes the sleeve 57 to actuate the mechanism which starts and stops the feeding of the stock 35 into the machine.

It will be observed that the connections 130

between the actuating piston 1, and the stock feeding rolls is a resilient yielding connection due to the spring 60 which yields under the pressure of nut 59 and the resistance to 5 movement of sleeve 57 due to the engagement of the stock feeding rolls with the stock. It will be observed also that when the actuating piston operates in the direction to move the stock feeding rolls out of engagement with 10 the stock, the spring 60 causes the stock feeding rolls to remain in yielding engagement with the stock during part of the movement of the piston in this direction.

By employing the adjustable tappets 58, 15 59 and a resilient yielding member in the connections between the common actuating member, piston 1, and the stock-feeding rolls, the advantages of yielding friction-feed of stock and adjustable lost-motion between the 20 stock-feeding and stock-chucking means are secured which permits the desired "timing" of the stock-feeding and chucking operations.

When the piston 1 is in the position shown 25 in Fig. 1 the cone wedge 31 has forced the fingers 32 apart causing the chuck to grip the stock and the feeding rolls 36, 37 are out of contact with the stock 35. When the control valve is turned to cause the fluid under pressure 30 to move the piston 1 to the opposite end of cylinder 4 the cone wedge will be withdrawn from between the fingers 32, the grip of the chuck upon the stock will be released, the washer 61 will push against the sliding sleeve 57 causing it to move and carry with it the lower end of downwardly extending portions 54 of arms 53. Thus the roll 37 will be forced up against the stock 35 and through the action of the above described gear segments 35 the roll 36 will be brought down on top of the stock 35. The chuck being now released and the rotating rolls 36 and 37 in contact with the stock 35, the stock will be fed through the hollow spindle of the machine until the valve is turned and the rolls 40 removed from contact with the stock or until the end of the stock strikes a stop 62 as shown in Fig. 1. When the stock strikes such a stop the rolls will continue to rotate but will slip 45 on the stock and not feed it forward.

The spring 60 and washer 61 are interposed 50 between the nut 58 and the sliding sleeve 57, thus providing a yielding spring pressure of the feed rolls upon the stock. This allows the rolls to pass easily over any slight irregularities in the stock, allows the rolls to slip when the stock is stopped and also serves to hold the rolls in contact with the stock for a short time after the piston starts to move the 55 chuck closing mechanism. When the stock strikes the stop 62 it tends to rebound from it and to destroy the accuracy of stock measurement. The action of the spring 60 overcomes this difficulty as although the stock 60 may strike and rebound from the stop and at

the same instant the valve may be thrown to release the feed rolls and start the chuck-gripping stroke, the spring 60 will keep the rolls in feeding contact with the stock long enough to again push it against the stop and 70 hold it there until the chuck grips it. This feature of my invention is of special advantage where the control valve is operated automatically when the stock strikes the stop. 75

Due to the provision of the above described 80 adjustable lost-motion and resilient yielding connections it is possible to vary the cycle of the stock-feeding and the stock-chucking operations as follows: The tappets 58 and 59, 85 may be set so that when piston 1 moves to the right as seen in Fig. 1, the feed rolls will first release and then the chuck will grip the stock; and when piston 1 moves to the left as seen in Fig. 1, the chuck will first release and then the feed rolls will engage the stock. Or, the tappets 58 and 59 may be set so that 90 they, in combination with spring 60, when piston 1 moves to the right as seen in Fig. 1 will first cause the chuck to grip the stock and then the feed rolls to release it; and when piston 1 moves to the left they will first cause the feed rolls to engage the stock and then the chuck to release it. The advantage of 95 this wide range of adjustments, especially in machines having automatically operated valves, will be understood by those skilled in the art.

I claim:—

1. Stock-feeding and chucking apparatus comprising a chuck adapted to grip the stock, 100 chuck-operating means, a driven stock-feeding roll adapted to engage the stock to feed it through the chuck, a fluid pressure cylinder, a source of supply of fluid under pressure, means controlling the flow of fluid into and out of said cylinder, a piston in said cylinder, connections between said piston, 105 said stock-feeding roll and said chuck-operating means, comprising a piston rod, adjustable tappets on said rod, a lever pivoted to a 110 fixed support, having one arm adapted to be engaged and moved by said tappets and the other arm adapted to move said stock-feeding roll into and out of engagement with the stock, a second lever pivoted to a fixed 115 support having one arm connected to said piston rod and another arm connected to said chuck-operating means, and a spring interposed between one of said tappets and the arm of said roll operating lever.

2. Stock-feeding mechanism comprising a stock-feeding roll adapted to engage and feed the stock, means for rotating said roll, roll-operating means for moving said roll into and out of engagement with said stock and yielding lost motion connections between said roll and said roll-operating means.

3. In a roller feed mechanism for feeding stock into machine tools, a driven roll, fluid-pressure-actuated means for causing said roll 120

to contact with or be removed from contact with said stock and a spring interposed between said roll and said fluid-pressure-actuated means to provide a resilient spring pressure of said roll upon the stock.

4. Stock-feeding mechanism comprising a driven stock-feeding roll, a support for said roll, fluid-pressure-operated means acting upon said support to move said roll into and out of contact with the stock, and a spring interposed between said support and said fluid-pressure-operated means whereby said roll exerts a yielding pressure on said stock.

5. Stock-feeding and chucking mechanism comprising a driven stock-feeding roll, a stock-gripping chuck, a source of supply of fluid under pressure, a cylinder, a piston in said cylinder, fluid conducting connections between said source of supply of fluid under pressure and said cylinder, means controlling the action of said fluid under pressure on said piston, link and lever connections between said piston and said chucking and feeding mechanism and yielding stock-feeding roll pressure creating means interposed in said connections between said piston and said stock-feeding roll.

6. Stock-feeding and chucking apparatus comprising a stock-feeding roll adapted to be moved into and out of contact with the stock, a chuck adapted to grip and be released from gripping said stock, a single fluid pressure operated cylinder and piston connected to cause the movement of said roll and the gripping and releasing of said chuck, a spring in the connections between said piston and said roll adapted to provide spring pressure of said roll on said stock, and means for causing the spring pressure of said roll on said stock to continue after the gripping action of said chuck has started.

7. Stock-feeding and chuck mechanism for machine tools comprising a chuck, a roller-feed, a single fluid-pressure-actuated piston in a single cylinder, mechanical connections whereby movement of said piston in one direction causes said chuck to grip the stock and then said roller-feed to be disengaged from the stock, and movement of said piston in the opposite direction causes said roller-feed to engage the stock and then said chuck to be completely released, and adjustable lost motion in said mechanical connections.

8. Stock-feeding and chucking mechanism for machine tools comprising a chuck, a roller feed, a single fluid-pressure-actuated piston in a single cylinder, mechanical connections whereby movement of said piston in one direction causes said chuck to grip the stock and then said roller feed to be disengaged from the stock and movement of said piston in the opposite direction causes said roller feed to engage the stock and then said chuck to be completely released, adjustable lost mo-

tion in said mechanical connections and a spring adapted to be compressed when said stock is being fed and to hold said roller feed in stock-feeding position until after said chuck has gripped said stock when said piston is making its stock-gripping stroke.

9. Stock-feeding and chuck mechanism of the class described comprising a driven stock-feeding roll, a stock-gripping chuck, a source of supply of fluid under pressure, a cylinder, a piston in said cylinder, means controlling the action of said fluid under pressure on said piston, connections whereby movement of said piston in one direction causes said stock-gripping chuck to disengage the stock and said driven stock-feeding roll to engage the stock and movement of said piston in the opposite direction causes said stock-gripping chuck to engage the stock and said driven stock-feeding roll to disengage the stock, and adjustable lost motion in said connections.

10. In apparatus of the class described, a driven stock-feeding roll, an adjustable support for said roll, a stock-gripping chuck, chuck-operating means, an actuating member for said roll support and said chuck-operating means, positive motion connections between said actuating member and said chuck-operating means, resilient yielding connections between said actuating member and said roll support, and means for adjusting the connection between said actuating member and said roll support to vary the time of its movement relative to the movement of said chuck-operating means.

11. Stock-feeding and chucking apparatus comprising a chuck adapted to grip the stock, chuck-operating means, a driven stock-feeding roll adapted to engage the stock to feed it through the chuck, a fluid-pressure cylinder, a source of supply of fluid under pressure, means controlling the flow of fluid into and out of said cylinder, a piston in said cylinder, connections between said piston, said stock-feeding roll and said chuck-operating means, comprising a piston rod, adjustable tappets on said rod, a lever pivoted to a fixed support, having one arm adapted to be engaged and moved by said tappets and the other arm adapted to move said stock-feeding roll into and out of engagement with the stock, and a second lever pivoted to a fixed support having one arm connected to said piston rod and another arm connected to said chuck-operating means.

12. In a machine tool having a hollow rotating spindle through which the stock is fed, fluid-pressure-operated stock-feeding and chucking mechanism comprising a source of supply of fluid under pressure, a cylinder, connections between said source of supply of fluid under pressure and said cylinder, a piston in said cylinder, a piston rod attached to said piston, a cross-head attached to said

piston rod, a link pivotally connected at one end to said cross-head, a lever pivotally connected at one end to the other end of said link, a fixed fulcrum for said lever, a chuck 5 adapted to be operated by the movement of the end of said lever which is not connected to said link, a stock-feeding roll mounted on one end of a pivoted arm, the other end of said pivoted arm being pivotally attached to 10 a sleeve adapted to slide on said piston rod, adjustable stops on said piston rod limiting the sliding movement of said sleeve, a spring on said piston rod between said sleeve and one of said stops and means for controlling 15 the action of said fluid under pressure on said piston.

13. Apparatus for controlling the stock-feeding and chucking operations of machine tools comprising a continuously rotating 20 stock-feeding roll adapted to be moved into and out of engagement with the stock to be fed, a chuck adapted to grip the stock, a supply of fluid under pressure, a cylinder, a piston in said cylinder, fluid conducting connections between said supply of fluid under pressure and said cylinder, means for controlling 25 the action of said fluid under pressure on said piston in said cylinder, and mechanical connections whereby movement of said piston in one direction moves the stock-feeding roll 30 into engagement with the stock and releases the chuck, and movement of the piston in the other direction moves the stock-feeding roll

out of engagement with the stock and causes the chuck to grip the stock. 35

14. Stock-feeding and chucking mechanism comprising a driven stock-feeding roll, a stock-gripping chuck, means for moving said roll into and out of engagement with the stock, means for operating said chuck to grip and to release said stock, reversible actuating means connecting said roll-moving and chuck-operating means adapted when operated in one direction to cause the chuck to grip and the roll to move out of engagement with the stock and when operated in the other direction to cause the chuck to release and the roll to engage the stock and a spring between said actuating means and said roll whereby the roll yieldingly 40 engages the stock. 45

15. Apparatus for controlling the stock feeding and chucking operations on machine tools comprising a continuously rotating stock feeding roll, a chuck adapted to grip 55 the stock, a supply of fluid under pressure, a cylinder, a piston in said cylinder, connections between said supply of fluid under pressure and said cylinder, means for controlling the action of said fluid under pressure on said piston in said cylinder and mechanical connections whereby movement of said piston controls the stock feeding action of said roll and the stock gripping action of said chuck. 60

EARL J. HORNBERGER.
